ATOMIZING APPARATUS

Marshall E. Callander, Columbia, Mo.

Application January 20, 1943, Serial No. 473,044

15 Claims. (Cl. 299—141)

This invention pertains to atomizing apparatus which is applicable to various purposes. Two specific applications will be described herein. One of these is the atomization of liquid fuel for oil burners and the like, and the other is to the manufacture of mineral wool and the like by the method in which a blast of air, steam or other suitable fluid is directed against a stream of molten material.

By this method as ordinarily practiced a stream of molten material, such as rock, slag, glass, etc., is permitted to fall from an outlet of a suitable cupola or furnace in which the material is melted. As the stream of molten material drops from the outlet of the furnace, a blast is directed against it transversely. Ordinarily steam is employed for forming such a blast, although air and other fluids have been used. When properly directed and controlled, the blast breaks up and disintegrates the molten material and forcibly projects it in the direction of the blast. As a result of this treatment, the material is not only broken up into small particles but is "spun" into fine fibers which, collectively, are known as "mineral wool."

The quality of the wool formed depends, to a considerable extent, upon the type of blast employed, and nozzles of various designs adapted to form the blast in different ways have been tried and used. One of the difficulties heretofore encountered has been the formation of substantial quantities of "shot" which are bodies of the molten material which seemed not to fiberize and hence solidified in globular form. Another difficulty has been the tendency of the molten mineral material to form encrustations upon the nozzle with the result that periodically when such encrustations have grown to substantial size they break off and are projected along with the blast. Consequently the resultant mineral wool is contaminated with such shot and slugs which it is frequently impossible to remove.

In my prior patent, No. 2,076,445, I disclosed a nozzle in which the jet passages are arranged generally according to the configuration of the arabic numeral 6. The nozzle there disclosed, however, represented only a partial solution to the problem. While the production of shot was thereby decreased, such a nozzle shows a tendency to become encrusted particularly at the lower portions thereof with a result that the mineral wool is frequently contaminated with "slugs." The nozzle disclosed in said patent, however, presented a difficult manufacturing problem and required to be drilled by an expert, generally the

inventor himself. This difficulty was due to the inclination of the orifices in two directions which, together with its peculiar configuration, rendered it impossible to lay out the drilling job with instructions sufficiently explicit that an ordinary mechanic could drill the holes properly.

The object of the present invention, generally stated, is to provide a nozzle of the character in which a plurality of jet openings inclined in two directions may be economically and readily manufactured; and to provide a method of manufacturing such a nozzle.

Another object is to provide such a nozzle which will minimize the production of shot and slugs.

15 A further object is to provide a nozzle adapted to form a blast having a swirl or vortical action.

Further objects will appear from the following description taken in connection with the accompanying drawings in which:

20 Figure 1 is a diagrammatic view illustrating the relation of the nozzle of the present invention to a cupola or other furnace employed in the manufacture of mineral wool.

Figure 2 is an end view of a nozzle embodying 25 this invention.

Figure 3 is a section on line 3—3 of Figure 2.

Figure 4 is an enlarged side view illustrating the formation of the blast in accordance with this invention.

30 Figure 5 is a diagrammatic view similar to Figure 1 but illustrating the application to oil-burners.

Figure 6 is a view, somewhat diagrammatical in form, illustrating the disposition of the nozzle 35 on the work table of a drill press for drilling according to the present invention.

Figures 7 and 8 are sectional views somewhat similar to Figure 3, showing modified forms of the nozzle tip.

40 The present invention contemplates the provision of a nozzle arranged to project a blast consisting of a series of individual jets against a falling stream of material to be atomized, such as molten rock, slag or glass, in the case of the manufacture of mineral wool. In accordance with the present invention, the series of jets which, together form the blast, are arranged so

45 as to impart to the particles of material operated upon, a swirling movement in addition to projection in the general direction of the entire blast and in such manner as to minimize collision of the atomized particles in their trajectory. This is accomplished by providing a series of jet passages in the end wall of a nozzle member with 50 the series of jet passages arranged in a generally 55

circular pattern, the center of which will herein be referred to as the axis of the nozzle it being understood, however, that such nozzle axis need not be concentric with the physical structure of the nozzle member itself. These individual jet passages have their inclinations varying progressively away from normal to a plane perpendicular to the axis of the nozzle which, in the case of a flat face nozzle, will mean that the individual jet openings are inclined progressively away from perpendicular to the nozzle face as will be hereinafter more fully described. The direction of the individual jet openings may vary in either the angle made with a plane perpendicular to the nozzle axis or in the angle made with a plane which includes a parallel with the nozzle axis; the former will be referred to herein as "inclination," the latter as "azimuth."

The jet openings are formed as bore holes in the end wall of the nozzle. These bore holes are small cylinders whose axes lie in the arc of a circle, but the axes of these cylinders do not constitute elements of a cone because they are so directed as to avoid intersection in space. In other words, the axes of the bore holes, as projected in space, are tangent to a virtual cylinder of smaller radius than the arcuate pattern of jet openings in the face of the nozzle.

Referring to the drawings, a cupola C having a spout D is provided for melting the material which when properly fluid is permitted to flow out of the spout D in a stream indicated at J. The nozzle comprises a blast tube F connected with any suitable source, not shown, of supply of pressure fluid, such as steam, and a cap or head G partly closing the end of the blast tube F. The head G has an end wall H, and this wall is perforated with a series of holes passing therethrough, each of which provides a passage for a jet of the pressure fluid which in the present illustration will be assumed to be steam. These jet passages have their exit openings from the outer face of the wall H arranged in a pattern as shown in Figure 2, in which these openings are numbered 1-16 inclusive.

In laying out the nozzle according to the present invention, a circle I may be described upon the face of the head G, the center of such circle being arbitrarily positioned, but in the embodiment shown in the drawings, it is substantially concentric with the face of the head. The radius of the circle I will depend upon the capacity, which it is intended that the nozzle should have, and other conditions and operations understood by those skilled in the art but, for the purpose of this disclosure, may be understood to be as on the order of one-half inch. The circle I provides the general pattern of arrangement of a plurality of jet openings 1 to 16, all of which except opening 1, lie on, or substantially on, circle I while opening 1 is disposed outside circle I and preferably directly above opening 2. It will be understood that, in view of the variation in direction of the respective openings 2 to 16, inclusive, only the exterior mouths of these openings will lie on, or substantially on, circle I. In case the face of the nozzle is not flat, or substantially flat, the exterior mouths of these openings may not actually lie in a circle but, if projected to some imaginary plane, would lie in a circle.

After the respective jet openings 1 to 16 inclusive have been located on the face of the nozzle, their respective azimuths must be determined and indicated. In the case of opening 1, the direction is substantially perpendicular to the face

of the nozzle. On the down-sweep of the pattern of openings, the azimuths of a few, for instance 2, 3 and 4 as shown in the drawings, are substantially parallel and make an angle of not over 30°, and preferably about 10°, to the horizontal indicated as line WE in Figure 2. These azimuths may be inscribed on the face of the nozzle.

To locate the azimuths of jet openings 5 to 16 inclusive, another circle K is inscribed upon the face of the nozzle. In the embodiment illustrated, the circle K is of smaller radius than the circle I and is eccentric with circle I, its center being located in the quadrant diagonally opposite the quadrant at which the stream of material J, to be atomized enters. The degree of eccentricity of the circle K with the circle I may be from a sixteenth to half the radius of the circle I.

The diameter of the circle K will affect the operation of the nozzle in that the greater the diameter of the circle K, the less the spread of the blast to be produced and vice versa.

From the indicated locations of the mouths of openings 5 to 16, inclusive, lines are drawn tangent to circle K. These tangents indicate the azimuths of the respective openings 5 to 16 inclusive.

The jet passages may be formed by drilling holes in the wall H of the head G, by arranging the head on a work table which is adjustable to various angles with the horizontal and drilling vertically as shown diagrammatically in Figure 6. Such a work table may be provided with a bottom plate P which may rest upon a support Q of a drill press or other suitable apparatus. An angle plate R is mounted upon plate P by suitable hinging means (not shown) and is adjustable angularly to vary the angle α between the plates R and P. The head G will be rotatably supported in any suitable manner upon plate R so that, by adjusting the angle α , the nozzle axis A is adjusted to the same angle with the vertical and therefore with the axis of a vertical drill T. Consequently, adjustment of the plate R at a given angle α , positions the face of the nozzle at the same angle out of normal with the drill T. The rotary setting of the head G may be guided by a scale U on the plate R.

With this arrangement of parts and with the plate R adjusted for a given inclination of any of the openings in the wall H of the nozzle, the azimuth lines may be aligned with the drill T by sight. Such alignment of the respective azimuth lines with the drill T will require, not only rotation of the head G relative to plate R, but will require relative translation thereof, as by sliding the plate P between guide rails V.

In the embodiment illustrated in the drawings, the inclination of jet openings 1 to 5 inclusive progressively increases away from normal to a plane perpendicular to the axis A; the departure of opening 1 from such normal being 0°, that of opening 2 being 5°, that of opening 3 being 10°, that of opening 4 being 15°, and that of opening 5 being 18°. In the embodiment illustrated, however, the inclination of openings 5 to 16 inclusive is the same, namely, 18°. These are the angles α which determine the adjustment of plate R relative to plate P in drilling the respective holes.

With a nozzle drilled as just described, it will be observed that the axes of the respective holes 1 to 16 inclusive vary progressively in direction but in such manner that such axes, when projected in space, do not intersect. In the case of

openings 5 to 16 inclusive, planes including the individual axes (of the respective holes) and a parallel to axis A are respectively tangent with an imaginary cylinder whose trace on the face of the nozzle is indicated by circle K, but the point of tangency between the respective individual axes and such imaginary cylinder is outwardly beyond the face of the nozzle. It will be seen, by virtue of this arrangement, the blast as a whole, as formed by these jets, is an elongated swirl having a constricted waist as indicated in Figure 4 and therebeyond flaring outwardly in the form of a generally tubular blast.

The jet openings 5 to 16, inclusive, are sufficiently close together to give continuity to the swirl. In the embodiment shown, openings 6 to 16, inclusive, occupy substantially 180° of the pattern, so that the openings are considerably less than a half radian apart.

It is important to so position opening 16 and circle K that the azimuth of opening 16 is directed below opening 1 unless auxiliary provision is made for preventing upward escape of the swirling particles in the blast.

The number and displacement of openings will depend, as indicated hereinabove, upon the capacity of the nozzle it being important that the openings, whose azimuths are tangent to the inner circle K, extend throughout the quadrant (southeast in the embodiment illustrated) diagonally opposite the quadrant at which the material to be atomized enters (northwest in the embodiment illustrated) and also extend into the quadrants below the entrance quadrant and laterally of the entrance quadrant.

It is desirable that the openings, whose azimuths are tangent to circle K, embrace at least 180° of the pattern of openings. For example, in the embodiment shown in Figure 2, the openings 6 to 16, inclusive, whose azimuths are tangent to the circle K, occupy more than 180° of the circle I and their points of tangency with the circle K embrace more than 180° of the latter. Such an arrangement assures that the swirl will re-enter itself.

It is contemplated that auxiliary jet openings may, when and if desired, be used in addition to the pattern of openings herein described.

The nozzle herein disclosed is of high capacity per volume of blast fluid and its operation is characterized by a high yield of spun material so that contamination of the mineral wool by shot or slugs is markedly reduced over that heretofore attainable as by the nozzle disclosed in my aforesaid patent. Reduction in the yield of slugs is believed to be attributable to the absence, in the nozzle of this invention, of any individual jet directed downwardly at a substantial angle which would tend to project the falling molten material downwardly. On the contrary, in the nozzle of the present invention, the jets, which first impinge the molten material, are directed so that their lateral force components are far in excess of their downward force components.

The reduction in the yield of shot over that attained with nozzles of my prior patent may be attributable to the fact that, whereas, in the case of said prior patent the individual jets were arranged so as to converge at a point or points with other jets; in the present case the individual jets are arranged so that there is less tendency for collision of the atomized particles in their trajectory. Furthermore, the arrangement of openings and their directions is such as apparently increases the strength of the vortical

action and gives the material an increased outward velocity from the nozzle as it passes through the waist portion of the blast and into the flared portion therebeyond.

5 While the illustrated embodiment has been described with particularity, many variations in structure and arrangement are permissible without departure from the spirit of the invention. The number of jet passages may be varied. This 10 may frequently be desirable when the size of the nozzle itself is changed. For instance, twelve jet passages may be used on a small size nozzle with good effect. Obviously the arrangement can be reversed so that molten material enters at the northeast quadrant instead of the northwest quadrant as illustrated, with the result that the material will be swirled in a clockwise rather than a counterclockwise direction as illustrated. This 15 is sometimes of advantage where several blasts are used simultaneously to distribute the material into the same receiving space as the blast sometimes tends to take a direction slightly angular to the axis of the nozzle and this can be corrected to some extent by using nozzles producing opposite swirls.

20 In applying this invention to oil-burners, an arrangement such as illustrated in Figure 5 may be used. In this figure, the blast tube F is connected to a blower L or other suitable source of pressure fluid such as air. In this case also, steam or other suitable fluid may be employed under proper circumstances. A fuel supply pipe M connected to any suitable source of supply is connected to a spout or nozzle O by which the 25 liquid fuel is projected into the blast formed by the head G. In Figure 5 the device is illustrated so that the nozzle O has practically the same relation to the head G that the spout D has as shown in Figure 1, and in this case the fuel delivered by the nozzle O simply falls into the blast 30 so as to be struck thereby while falling. So long as this relation of the nozzle O to the head G is maintained these elements may have any desired position, that is, the nozzle O may project 35 its stream horizontally or in any other direction, under suitable pressure in the supply pipe M, in which case the head G will be oriented accordingly.

40 It has been found that when used in this way to atomize fuel oil this nozzle accomplishes very complete atomization, so much so that in fact the fuel appears to be almost completely vaporized by the action of the blast. Accordingly, when this finely atomized fuel is ignited, a strong 45 flame is produced and complete combustion is easily obtained.

50 In this case also the relation of the openings is such that the blast is formed by a succession of narrow jets arranged progressively in an orderly progression as already described, such progression being downwardly in Figure 2 and in Figure 5 in a direction transverse to the direction of the blast as a whole. The stream of liquid fuel is then projected into the blast in a direction 55 which is initially along this direction of progression of the jets of the blast. Accordingly, the fuel is struck by these jets in succession and an action similar to that described for mineral wool takes place except that, since the fuel liquid is

60 usually of less viscosity than the molten material from which mineral wool is made, the result of impact is probably more of a shattering effect which breaks up the fuel into extremely minute particles which apparently vaporize at once.

65 70

75 It has been found that in operating with some

types of material which have a high melting point, the heat of the material in the stream J seems to heat up the nozzle tip to an excessive temperature. In some instances the material may show a tendency to adhere to the face of the nozzle where it collects to form slugs which may later be expelled and included in the fiberized material. Furthermore, the excessive heat tends to deteriorate the nozzle itself, which may become burnt at a point adjacent to the jet passages. In such situations it is advantageous to form the nozzle tip as shown in Figures 7 and 8. In these figures the middle portion of the end wall H of the nozzle is thickened. Its thickness at this point may be several times that of a nozzle such as shown in Figure 3. At the same time, the outer face of the tip is made convex as by rounding it as shown in Figures 7 and 8. In Figure 7 the inner face of the end wall H is square with the axis, while in Figure 8 this inner face is rounded to conform generally to the outer face.

Nozzle tips such as shown in Figures 7 and 8 are comparatively free from the trouble of adhesion of the material thereto and show less tendency to become burnt. This is probably due to the fact that the jet passages have a longer travel through the thickened portions of the nozzle, and the gas passing therethrough is effective in cooling the nozzle so as to prevent excessive temperatures. At the same time, the convex outer surface promotes a movement of the surrounding air over that surface and toward the issuing jets, and this moving air apparently also has a cooling effect which prevents an excessive temperature rise in the nozzle tip.

While the invention has been described with particular reference to the manufacture of mineral wool and for the atomization of fuel oil, it is apparent that the nozzle may be applied otherwise. Since it is obvious that various changes may be made in the details of construction and that the nozzle may be supplemented without interfering with the advantageous action herein described, it is to be distinctly understood that such modifications and additions as to not depart from the spirit of this invention are, although not specifically described herein, contemplated by and within the scope.

Having thus described the invention, what is claimed is:

1. An atomizing nozzle of the character described, comprising, a blast-tube head having an end wall transverse to the nozzle axis, said wall having a series of jet passages therethrough arranged in a circuit around the nozzle axis and having progressively different directions so that the axes of the respective passages do not intersect, the exterior mouths of said jet passages being located inwardly of the interior mouths thereof.

2. An atomizing nozzle of the character described, comprising, a blast-tube head having an end wall transverse to the nozzle axis, said wall having a series of jet passages therethrough arranged in a substantially circular arc around the nozzle axis and having progressively varying directions such that the jets issuing from said passages cooperate to form collectively a waist, substantially as described.

3. An atomizing nozzle of the character described, comprising, a blast-tube head having an end wall transverse to the nozzle axis, said wall having a series of jet passages therethrough arranged in a substantially circular arc around the nozzle axis and having progressively varying directions such that the jets issuing from said pas-

sages cooperate to form collectively a tubular blast, substantially as described, the exterior mouths of said jet passages being located inwardly of the interior mouths thereof.

4. A nozzle of the character described, comprising, a blast-tube head having an end wall transverse to the nozzle axis, said wall having a series of jet passages therethrough arranged in a substantially circular arc around the nozzle axis and having progressively varying direction such that the jets issuing from said passages cooperate to form collectively a tubular blast flaring outwardly, the exterior mouths of said jet passages being located inwardly of the interior mouths thereof.

5. A nozzle for making mineral wool and the like, comprising, a blast-tube head having an end wall transverse to the nozzle axis, said wall having a series of jet passages therethrough arranged with their exit openings in a curve starting at one side of the nozzle axis and extending downwardly, then laterally toward the opposite side and finally upwardly on the opposite side of said axis, said passages on the downward part of said curve having their individual axes inclined to a plane normal to the nozzle axis at progressively decreasing angles (in a plane including the respective individual axis and a parallel to the nozzle axis), and those passages on the upward portion of said curve having their individual axes directed at uniform inclinations but at progressively varying azimuths.

6. A nozzle for making mineral wool and the like, comprising, a blast-tube head having an end wall transverse to the nozzle axis, said wall having a series of jet passages therethrough arranged with their exit openings in a curve starting at one side of the nozzle axis and extending downwardly, then laterally toward the opposite side and finally upwardly on the opposite side of said axis, said passages on the downward part of said curve having their individual axes inclined to a plane normal to the nozzle axis at progressively increasing angles, and those passages on the bottom portion of said curve having their individual axes directed at uniform inclinations but at progressively varying azimuths.

7. A nozzle for making mineral wool and the like, comprising, a blast-tube head having an end wall transverse to the nozzle axis, said wall having a series of jet passages therethrough arranged with their exit openings substantially in a circular arc concentric with and below said axis and having their individual axes inclined with respect to a plane normal to said nozzle axis and directed so as to be tangent to a cylindrical surface, which is eccentric downwardly and laterally with respect to said nozzle axis.

8. A nozzle for making mineral wool and the like, comprising, a blast-tube head having an end wall transverse to the nozzle axis, said wall having a series of jet passages therethrough arranged with their exit openings substantially in a circular arc concentric with and below said axis and having their individual axes inclined with respect to a plane normal to said nozzle axis and directed so as to be tangent to a cylindrical surface of smaller radius than said arc and which is eccentric downwardly and laterally with respect to said nozzle axis.

9. An atomizing nozzle of the character described comprising, a blast tube head having an end wall transverse to the nozzle axis, said wall having a series of jet passages therethrough arranged in a substantially circular arc around the nozzle axis and having progressively different di-

rections, none of said passages being directed downwardly at an azimuth greater than 30° to the horizontal.

10. An atomizing nozzle of the character described comprising, a blast tube head having an end wall transverse to the nozzle axis, said wall having a series of jet passages therethrough arranged in a substantially circular arc around the nozzle axis and having progressively different directions, the azimuth of a passage circumferentially remote from the entrance space being directed below at least one opposite jet.

11. An atomizing nozzle of the character described comprising, a blast tube head having an end wall transverse to the nozzle axis, said wall having a series of jet passages therethrough arranged in a substantially circular arc around said nozzle axis and having the azimuths of their individual axes progressively varying, said series of jet passages embracing at least 180° and so oriented that some of said jet passages are in the quadrants vertically below, laterally opposite and diagonally opposite the quadrant at which the material to be atomized enters.

12. A nozzle for making mineral wool and the like, comprising, a blast-tube head having an end wall transverse to the nozzle axis, said wall having a series of jet passages therethrough arranged with their exit openings substantially in a circular arc concentric with and below said axis and having their individual axes inclined with respect to a plane normal to said nozzle axis and directed

so as to be tangent to a cylindrical surface of lesser diameter and arranged interiorly of said circular arc.

13. A nozzle comprising a member having a series of bore holes therein whose axes are tangent to a virtual cylinder, said bore holes being spaced substantially uniformly less than a half radian apart throughout more than 180° of a substantially circular arc, said virtual cylinder being of smaller radius than said circular arc.

14. A nozzle comprising a member having a series of bore holes therein whose axes are tangent to a virtual cylinder substantially within the pattern of bore holes, said axes being non-parallel but non-intersecting in space, the points of tangence of said axes being in elements of said cylinder spaced less than a half radian apart throughout more than 180° thereof.

15. A nozzle comprising a member having a series of bore holes therein whose axes are tangent to a virtual cylinder substantially within the pattern of bore holes, said axes being non-parallel but non-intersecting in space, the points of tangence of said axes being in elements of said cylinder spaced less than a half radian apart throughout more than 180° thereof, the exterior mouths of said series of holes forming an unclosed curved pattern in the end face of the member, and means for introducing material to be atomized at the unclosed region of said pattern.

MARSHALL E. CALLANDER.
